UNITED STATES PATENT OFFICE.

JAY B. BEEL, OF CHICAGO, ILLINOIS, ASSIGNOR TO BEARDSLEE CHANDELIER MANUFACTURING COMPANY, OF CHICAGO, ILLINOIS, A CORPORATION OF DELAWARE.

DESIGN FOR SURFACE ORNAMENTATION FOR A CEILING PLATE OR SIMILAR ARTICLE.

60,847.

Specification for Design.

Patented Apr. 18, 1922.

Application filed December 11, 1920. Serial No. 430,054. Term of patent 7 years.

To all whom it may concern:

Be it known that I, JAY B. BEEL, a citizen of the United States, residing at Chicago, in the county of Cook and State of Illinois, have invented a new, original, and ornamental Design for the Surface Ornamentation for a Ceiling Plate or Similar Article, of which the following is a specification, reference being had to the accompanying drawing, forming a part thereof, the design relating to the ornamentation and being employed and more particularly shown applied to the part of a lighting fixture which may be employed as a wall or ceiling plate or a body shell, the design as disclosed in the enlarged fragmentary view, Figure 2, being employed on shells of varying shape or configuration as disclosed.

In the drawings—

Figure 1 is a plan view of a shell of a lighting fixture provided with my new design as hereinbefore described.

Figure 2 is an enlarged fragmentary view, in plan, of my ornamental design.

Figure 3 is a side view of the shell shown in Figure 1.

I claim:—

The ornamental design for the surface ornamentation for a ceiling plate, or similar article as shown and described.

JAY B. BEEL.
